UNITED STATES PATENT OFFICE.

EDWARD I. GOLDBERG, OF NEW YORK, N. Y.

AIR-PURIFIER.

1,196,539.

Specification of Letters Patent. Patented Aug. 29, 1916.

Application filed September 28, 1915. Serial No. 53,081.

To all whom it may concern:

Be it known that I, EDWARD I. GOLDBERG, a citizen of the United States, and a resident of the city of New York, borough of 5 Manhattan, in the county and State of New York, have invented a new and Improved Air-Purifier, of which the following is a full, clear, and exact description.

This invention relates to respirators or 10 air purifiers and has particular reference to means whereby a man is enabled to live a considerable length of time in an atmosphere which would otherwise be intensely disagreeable or dangerous.

15 More specifically stated, the invention comprises a casing adapted to be carried upon a person or in some other convenient position, the casing containing air purifying devices or chemicals, depending upon the 20 character of the poisons or dangerous atmospheric conditions, and tubular connections being provided between the casing and the man's mouth and nostrils.

With the foregoing and other objects in 25 view, the invention consists in the arrangement and combination of parts hereinafter described and claimed, and while the invention is not restricted to the exact details of construction disclosed herein, still for the 30 purpose of illustrating a practical embodiment thereof, reference is had to the accompanying drawings, in which like reference characters designate the same parts in the several views, and in which—

35 Figure 1 is a perspective front view showing the device in operation; Fig. 2 is a similar rear view; Fig. 3 is a vertical sectional view of the casing; Fig. 4 is a detail sectional view of the apparatus adjacent the 40 person's mouth and nose; Fig. 5 is a front elevation corresponding to Fig. 4; Fig. 6 is a horizontal section on the line 6—6 of Fig. 5; and Fig. 7 is a perspective view of the nose piece.

45 At 10 I show a casing adapted to be closed and sealed, except as otherwise hereinafter specified, by any suitable means and comprising any desired number of interior compartments. This casing may conveniently be carried upon one's back by means of 50 straps 11 and 12. It will be understood, however, that the position of the casing or manner of supporting or carrying it may be variously determined.

At 13 I show in the top of the casing an 55 air inlet and at 14 I show several outlets for purified air.

Without being unnecessarily limited as to the number of purifying elements of any particular apparatus, the illustration covers 60 two containers 15 and 16 each having a neck 17 and a stopper 18. In each of the necks is fitted a guard 19 of tubular tapered form having a restricted mouth at its lower end. The air inlet 13 leads through a tube 20 into 65 the first guard 19, and to the lower end of the tube 20 is secured a flexible tube 21 leading through the restricted mouth of the guard and comparatively close to the bottom of the receptacle 15, the guard protect- 70 ing the flexible tube and preventing the splashing of the liquid into the mouth of the container or receptacle. This tube 21 being flexible provides that its free end will always reach approximately to the bottom of the 75 liquid in the container irrespective of the inclination of the casing or position of the wearer. The mouth of the guard 19 is spaced sufficiently from the flexible tube 21 to permit the partially purified air to pass 80 upwardly between the tube and guard whence it is conveyed by means of a tube 22 into the other receptacle down through the guard 19 thereof and flexible tube 21 for a 85 second treatment. The air is thence conveyed upwardly through the neck of the receptacle 16 by means of a tube 23 into the bottom of a filter 24 and thence to the outlets 14.

Flexible tubes 25 lead from the outlets 14 90 to the nose and mouth piece indicated as a whole at 26. This device includes a nose piece 27 adapted to fit sufficiently snugly over the nostrils and bridge of the nose and having a tubular lower end 28. The nose 95 piece 27 is preferably formed of rubber or similar material adapting it to be fitted in position. The tubular connection 28, however, is of some rigid material and is provided at its lower end with a valve 29 adapted 100 to open downwardly freely to the atmosphere but prevent entrance of air upwardly thereto.

At 30 is indicated a bar or plate serving as a holder for the tubular connection 28 105 and also elbow members 31 to which the upper ends of the tubes 25 are connected.

At 28' is indicated a central horizontal

extension communicating with the tube 28 and adapted to project into the person's mouth.

The ends of the elbow members 31 opposite the connections 25 are provided with valves 32 which lie on opposite sides of the extension 28' between the person's lips or within his mouth.

From the construction shown and described it follows that the operator can freely inhale through his mouth, the direction of inspiration being through the tubes 25, elbow members 31, and valves 32. The exhalation may be either from the mouth through the extension 28', pipe 28 and valve 29, or through the nose through the pipe 28 and valve 29.

Obviously the character of the purifying means in the containers 15, 16 and 24 may vary greatly according to local conditions, and without in any manner restricting the scope of the invention I may state briefly a few illustrations of the practical adaptations of the device. The filter may contain layers of cotton 33 or other suitable fibrous material and an intermediate layer of charcoal 34 or the like. The receptacles 15 and 16 contain liquid 35. As a precaution against ordinary dust, dirt, or smoke, the liquid may be water. As a guard against sulfuric acid fumes I may use sodium or potassium hydroxid, 10% solutions. As a guard against ammonia I may use a 5 or 10% solution of hydrochloric acid. As a precaution against air poisoned with chlorin, bromin, iodin, or fluorin, I may use a saturated solution of sodium thiosulfate.

I claim:

1. In an air purifier, the combination of a casing, means to support the casing upon a person, the casing having an air inlet and an air outlet, air purifying means within the casing comprising a receptacle adapted to contain liquid, and a tapered tubular guard connected at its larger end to the mouth of the receptacle and extending downwardly therefrom, means to convey the air from the inlet through the liquid, said conveying means including a flexible tube adapted to depend irrespectively of the position of the casing, said guard protecting the flexible tube and preventing the liquid from splashing into the mouth of the receptacle, means to convey the air from the liquid to the outlet, a nose and mouth piece held in place over the nose by the mouth, and means to convey the purified air from the outlet to the nose and mouth piece.
2. In an air purifier, the combination of a casing having an air inlet and an air outlet, a receptacle within the casing having a neck and a plug closing the outer end of the

neck, said inlet constituting a tube leading through the plug and through the receptacle neck, a guard fitted in the neck and projecting thence inwardly into the receptacle, said receptacle being adapted to contain liquid for the purification of the air, a flexible tube connected to the inlet tube and extending thence through the guard adjacent the bottom of the liquid, and means extending from the neck plug to convey the purified air through the outlet.

3. In an air purifier, the combination of a casing having an air inlet and an air outlet, a plurality of receptacles within the casing each adapted to contain a quantity of purifying liquid and each having an upwardly projecting neck closed by a stopper, and each receptacle having a guard extending inwardly from the neck, said inlet constituting a tube projecting through one of the stoppers into the guard pertaining to such receptacle, a tube connecting one plug to the other whereby air is conveyed from one receptacle to the other, said tube leading into the guard of the second receptacle, a pair of tubes connected respectively to the air inlet and the connecting tube and extending thence through the guards into the liquid, a filter, and means to convey the purified air from the second receptacle through the filter to the casing outlet.

4. In an air purifier, the combination with a casing having an inlet and an outlet, and purifying devices within the casing, of a nose and mouth piece comprising a nose shield, a depending tube communicating with the nose shield, said depending tube having a right angularly disposed extension adapted to project into the mouth, a holder secured to the extension, a mouth inlet carried by the holder, said inlet having a valve preventing outflow therefrom and said first mentioned tube having at its lower end a valve preventing inflow therethrough, and means connecting the outlet of the casing with said mouth inlet.

5. The combination with a casing having an inlet and two outlets, and purifying devices within the casing between the inlet and the outlets, of a nose and mouth piece comprising a nose shield, a pair of mouth inlets having valves preventing outflow therethrough, tubes connecting the mouth inlets with said casing outlets, and a single outlet tube communicating with the mouth and nose shield serving to permit exhalation through either the mouth or the nose, substantially as set forth.

EDWARD I. GOLDBERG.
